LOUNGE CHAIR

James E. Jones, Toledo, Ohio, assignor to The Hetrick
Manufacturing Company, Toledo, Ohio, a corporation of Ohio

Application December 13, 1954, Serial No. 33,490

Term of patent 14 years

(Cl. D15—1)

FIG. 1.

FIG. 2.

Figure 3 is a perspective view on a larger scale of the frame element only with the fabric portion omitted more clearly to illustrate the details of the frame.

I claim:

The ornamental design for a lounge chair, as shown.
